HINGE BUTT MORTISING MACHINE

William L. Grathwol, Stratford, Conn.

Application March 10, 1954, Serial No. 415,296

6 Claims. (Cl. 144—27)

This invention relates to a hinge butt mortising machine, and has for an object to provide a simple and effective device for recessing or mortising the free edge of a door or the face of a door jamb to receive the butt of a hinge.

Another object is to provide a device of this character which will facilitate the operation of cutting the mortise, and will insure that the bottom wall of the mortise or recess is flat and parallel with the edge of the door or face of the jamb so that the butt of the hinge is properly positioned and not inclined or tilted.

A further object is to provide a device in which the outline of the mortise or recess is accurately located and readily cut to exactly the proper depth and then the material within this cut outline is removed in a single operation at a proper and uniform depth.

A still further object is to provide a device by which the mortise is always located or positioned from the surface in which it is located to insure that the bottom of the mortise is parallel to this top surface and not tipped or inclined to it.

Another object is to provide an improved cutting edge for the knife used in cutting the bottom of the mortise, which will give a much better cut and cuts in such a way as not to tend to pull up and split the material at the outer ends of the mortise.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

In these drawings:

Fig. 1 is a top plan view of the portion of the device used in locating and cutting the outline of the mortise and showing it as it is used on the edge of a door;

Fig. 1a is a partial plan view of one end of the holder of Fig. 1 with the knife blade removed;

Fig. 2 is a bottom view of the device;

Fig. 3 is a front view looking from the left of Fig. 1;

Fig. 4 is a side view looking toward the bottom of Fig. 1;

Fig. 5 is a detailed section substantially on the line 5—5 of Fig. 3;

Fig. 6 is a section of an edge of the cutting knives on an enlarged scale;

Fig. 7 is a top plan view of the portion of the device used for making the bottom cut of the mortise to remove the material within the cut outline and showing it applied to a door jamb;

Fig. 8 is a longitudinal section substantially on line 8—8 of Fig. 7;

Figs. 9 and 10 are detail sections substantially on lines 9—9 and 10—10 respectively of Fig. 8;

Fig. 11 is a top plan view of a modified arrangement of the device;

2

Fig. 11a is a plan view of one end portion of the knife holding head with the upright blade removed;

Fig. 12 is a partial side view and partial section of the device of Fig. 11, and

Fig. 13 is a transverse section substantially on line 13—13 of Fig. 12.

The operation of properly cutting the mortise or recess for a hinge butt in a door or door jamb with the usual hand chisels is a difficult one and requires a skilled

operator, besides requiring considerable time. The present device is designed to quickly and accurately both outline the mortise and accurately remove the material within this outline by simple operations which may be performed by practically anyone, and so does not require a skilled operator. The operation of forming the mortise or mortised recess is performed in two steps. First the position of the mortise is properly determined, and then the mortise is outlined to the correct size of the hinge butt and then accurately cut to the proper depth to correspond to the thickness of this butt, and then the material within this cut outline is removed by a horizontal cut at the proper depth below the face or surface in which the mortise is being formed.

In the first form of this machine of Figs. 1 to 10, the

device for cutting the outline of the mortise is shown in Figs. 1 to 6, and the device for then making the cut at the bottom of the outlined mortise is shown in Figs. 7 to 10. The first device comprises a head 1 having means

for mounting three vertical knives 2 and 3 for making the two transverse end cuts and the connecting intermediate cut respectively, the intermediate cut made by the knife 3 being spaced inwardly from the side of the door or jamb, in the illustration the door 4, the proper distance corresponding to the width of the butt of the hinge to be mounted in it, and the blades 2 being spaced

to correspond with the length to this butt. The knife 3 is mounted on an upright wall surface 5 under an overhanging wall 6 by any suitable means such as screws 7, and the upper edge of the knife abuts the surface 6, as

shown in Fig. 5, so that the force of driving the knife into the material is transmitted from this wall to the blade instead of through the screws 7. The two end blades 2 are mounted on upright holders 8 each mounted in a recess

9 at the opposite ends of the head 1 for vertical sliding movement, and they are retained in the recess by spring plates 10 across the open side of the recess and secured by any suitable means such, for example, as the screws

11. These spring plates are normally transversely curved, as indicated in dotted lines at the lower part of Fig. 1, so that when they are clamped in position by setting up the screws 11 they are stressed and thus maintain a frictional spring pressure on the blade holders 8. These

holders are recessed on their lower ends and the blades 2 are mounted in these recesses with their top edges engaging the tops of the recesses so that the force of driving the blade into the woodwork of the door or jamb is transmitted directly from the holder to the top of the blade and not through the screw 12 for securing the blade in the holder. The lower end 13 of the holder engaging

the top surface 14 of the door 4, or if used on a door jamb 50 the top surface 50a thereof (Figs. 7 and 8) limits the downward movement of the cutter blade and determines the depth of cut, or this could be determined by

the head 8b of a stop pin carried by the holder engaging the top wall 1a of the head. The holder projects above the top of the head 1 as indicated at 8a and forms a striking head or surface to be hit by a hammer for driving the blade 2 into the wood of the door or jamb to the proper depth. A similar striking head or surface 15 is

provided on top of the head 1 for driving the connecting blade 3, and the depth of cut made by this blade is de-

terminated by the bottom walls 16 on the under side of the head engaging the top surface 14 of the door 4 or 50a of jamb 50. A handle or hand grip 17 is provided extending from the rear side of the head 1, that is, the side on which the knife 3 is located, for holding the head in position while driving the knives to make the cuts. On the front or opposite side at its opposite ends the head is provided with a pair of lugs 18 carrying positioning buttons 19 of any suitable material, which may be rubber or the like, or the metal heads of the screws 20 on which they are mounted threaded into the lugs 18. This permits a certain amount of lateral adjustment of the positioning heads or buttons 19 to position the distance of the knife blade 3 from the side surface 4a of the door 4 or 49 of jamb 50.

In use, the operator grasps the handle 17 and places this device on the top of the door or jamb with the positioning buttons 19 engaging the side surface of the door or jamb. This positions the blade 3 at the proper distance from the face of the door to correspond with the width of the hinge butt to be mounted, the longitudinal position being measured or otherwise determined, and by hammering on the lug or surface 15 the blade 3 is driven to the proper depth corresponding to the thickness of the hinge butt, its downward movement being limited, as previously indicated, by the bottom surfaces 16 of the head engaging the top surface of the edge of the door. The blades 2 are then driven in a similar manner by hammering on the upper ends 8a of the holders for these blades, and the depth of cut is determined by the lower end 13 of the holder engaging the top surface of the door or the head 8b of a stop pin on the holder engaging the top of the head. Then the device may be removed, leaving the outline of the mortise or mortise recess accurately located and cut to the proper depth to correspond with the thickness of the hinge butt. The overhanging surface 6 may be used as a lifting surface by the claw of a hammer to facilitate lifting and removal of the device after making the cuts. The cutting edges of the blades 2 and 3 are bevelled from opposite sides, as shown exaggerated in Fig. 6. The greatest bevel is at 21 on the inner side, and there is a slight bevel 22 on the outer side. This is so that when the knives are driven vertically into the wood they are not forced outwardly out of position, but the outline cuts are properly maintained in the proper location and to give the proper size to the outline of the mortise to agree with that of the hinge butt. The vertical meeting edges of the blades 2 and 3 are bevelled at an angle of 45° to meet properly as indicated at 3a.

After the outline cuts have been made, as indicated, a horizontal cut to form the bottom of the mortise or mortise recess to remove the material within the outline cuts and provide the bottom surface on which the butt of the hinge is mounted, is made by a fourth or horizontal blade 23, Figs. 7 and 8. This blade is movably mounted in a frame 24 comprising laterally spaced side bars 25 connected at one end by a transverse bar 26. Slidably mounted at the forward end between these bars is a transverse head or carrier 27 for the blade 23, this blade being mounted in a recess 28 in the bottom of this head and secured by suitable screws 29, the rear edge 30 of the blade engaging the inner wall of the recess so the force of moving the blade is imparted to this edge of the blade without relying on the screws, and taking the strain off the screws. At its opposite ends this head or holder 27 is slidably mounted on the side bars 25 by providing in the inner side of each bar a longitudinal channel or groove 31 and providing the head or holder 27 with corresponding ribs 32 sliding in these grooves. This head has laterally spaced upright lugs or extensions 33 forming bearings for a shaft 34 including toothed pinions or gears 35 meshing with racks 36 formed on top of the bars 25. At one end of the shaft 34 is a ratchet mechanism 37. In the arrangement shown this ratchet comprises a toothed gear 38 and mounted to swing on this shaft but enclos-

ing this gear is a head 39 from the outer side of which extends a handle 40 having a reduced inner end 41 slideable in bearings in the head 39, and at its inner end having a pawl 42 to engage the teeth of the ratchet gear 38. A spring 43 on the reduced portion 41 of the handle reacting at opposite ends against the head 39 and a washer 44 on the handle yieldingly retains the pawl 42 in engagement with the gear 38. At its outer end the head 39 is provided with a transverse slot 45 adapted to receive a pin 46 carried by the handle 40. The tooth 42 of the pawl is inclined on one side and straight on the opposite side, as shown in Fig. 8; so that in this position by swinging the handle clockwise or to the right as the straight side of the pawl 42 engages the tooth of the gear 38 it will rotate this gear to the right and with it the shaft 34 and the two gears 35, which, coacting with racks 36 will shift the head or holder 27 inwardly or to the right.

As the opposite side of the pawl 42 is inclined, reverse or counterclockwise movements of the handle 40 will not operate the shaft as the pawl will be merely forced outwardly and will slide over the teeth of the ratchet gear. The operator may, however, force the head in the opposite direction by first shifting the handle 40 outwardly against the action of the spring 43 to remove the pin 46 from the slot 45. This also removes the ratchet pawl 42 from the gear 38. Then by turning the handle 40 a half revolution the pawl 42 is reversed, bringing its straight side on the left side as viewed in Fig. 8. This also brings the pin 46 again into alignment with the slot 45 and the spring 43 will now force the pawl 42 inwardly into engagement with the gear 38. The ratchet arrangement has now been reversed so that swinging of the handle 40 back and forth will rotate the shaft 34 in the opposite direction or counterclockwise, and by action of the gears or pinions 35 on the racks 36 will shift the head 27 to the left or outwardly.

At its under side and below the blade 23 the head 27 has a transverse bar 47 provided with a convexly curved upright forward face 48 forming a positioning surface or stop to engage the side or face 4a of a door 4 or 49 of a jamb 50, this member 47 being shown as of a width corresponding to a door jamb in the drawing, but the operation would be the same against the side surface of a door. The head 27 also has a downwardly extending lug 51 carrying an adjustable stop screw 52 adapted to engage a forward stop wall 53 on the bar 47 to limit forward movement of the head 27 in its operation to the right to force the blade 23 into the door or jamb to form an under or horizontal cut under the material within the cut outline, indicated by the broken line 55, Fig. 7, as previously described and indicated at 54, Fig. 8, to form and clear the bottom surface of the mortise. To secure better operation and cutting effect of the blade 23 its cutting edge is inclined slightly inwardly from the opposite ends of the blade, as indicated at 56, Fig. 7.

While operating this blade, however, the frame 24 is clamped to the edge of the door 4 or the jamb 50. For this purpose there is provided in the frame a quickly adjustable clamp comprising a clamping bar or member 57 and a supporting bar or head 58, both being slideable on the side bars 25 of the frame and extending between these side bars. Each side bar 25 is provided on its top with a longitudinal rib 59 provided with a series of spaced notches 60 and the head 58 carries a transverse locking bar 61 which has reduced ends 62 adapted to seat in the notches 60, the bar 61 being retained against the rear side of the head 58 for limited upward movement by the angle shaped clips 63. The clamp or bar 57 has an upright side wall or face 64 to engage the opposite side of the door 4 or jamb 50 from the convex positioning surface 48. The head 58 and the transverse clamp 57 both overlap the top edges of the ribs 59 and are supported and slideable thereon, the head being held

against removal by a transverse plate 65 secured to the under side of the head by any suitable means, such as the bolts or screws 66, which may also be used for mounting the clips 63, and the opposite ends of this plate 65 overlap the under sides of the side bars as shown in Fig. 10, to retain the head on the frame. This head has a downwardly extending lug 67 in which is a clamping screw 68 having a swivel connection 69 with the clamping bar 57, and the screw may be operated by any suitable means, such, for example, as a slideable pin 70 forming a hand grip.

In using this clamp the head 58 and the clamping bar 57 are given a quick rough adjustment toward or against the side of the door 4 or jamb 50 by first lifting the locking bar 61 to remove its opposite ends from the notches 60 on the side bars of the frame. Then by dropping the end portions of bar 61 in the adjacent set of notches 60 the head 58 is locked against outward movement. Then by turning the screw 68 only a small amount the clamping bar 57 is firmly clamped against the jamb or door, securely clamping the device in place and securely and accurately holding it for the cutting operation previously described.

The under sides of the side bars 25 of the frame comprise surfaces 71 and 72 of different heights, the surfaces 71 resting against the top or edge surface 50a of the jamb 50 or top 14 of door 4 to position the frame thereon, while the curved surface 48 engages the side surface of the door or jamb and properly positions the device with respect thereto. The surface 48 is curved in a vertical plane convexly so as to give substantially a line contact with the face of the door or jamb, and thus insure proper location of the device even with an irregular side or nonvertical face on the door or jamb, which might not necessarily be true if this surface were a flat vertical surface. Also the recess or space formed by locating the surface 72 spaced above the surface 71 permits the use of the device on a door jamb which may have a rabbeted face or an intermediate projecting rib, indicated by the broken line 73 in Fig. 8, and therefore will properly locate the device without interference from this rib.

In the use of the device, after the outline cut has been made by the cutter of Figs. 1 to 6, and which outline is indicated by the broken line 55 in Fig. 7, the frame 24 is placed on the edge of the door or jamb with the curved surface 48 against one side face and the blade 23 lined up with its opposite ends in alignment with the opposite end cuts 55a of the outline 55. Then the clamp, including the head 58 and the clamping bar 57, are shifted against the opposite side of the door or jamb as previously described, and the clamp 57 set up tight by the screw 68. During this operation, of course, the head 27 is retracted to the left so that the edge of the blade 23 clears the side surface of the door or jamb. However, after the clamp is set this edge is at the proper distance below the top surface 14 of the door 4 or surface 50a of jamb 50 to correspond with the proper depth of the mortise to be cut in the door. Then by shifting the head 27 and with it the blade 23 to the right as viewed in Figs. 7 and 8, by operation of the handle 40 of the ratchet, as previously described, the edge of the blade 23 is forced into the door jamb as indicated in these figures, to accurately, smoothly and uniformly cut the material 54 within the outline cut 55 and remove it, accurately cutting the bottom surface of the mortise at the proper depth from and parallel with the top or edge surface 14 or 50a of the door or jamb, with a simple operation. After cutting this bottom of the mortise the head 27 and the blade 23 may be retracted or withdrawn by reversing the ratchet, as previously described.

The two portions of the machine for first making the outline cut of the mortise and then the bottom cut to remove the material within the outline cut are hinged

secured together in the form of Figs. 11 to 13. In this form the frame 74 corresponds to the frame 24 of the first form, except that at the rear end portion it has a pair of downwardly extending lugs 75 at the rear ends 5 of the side bars 25. Otherwise this frame is the same as that of Figs. 7 and 8 and carries the same head or holder 27 for the horizontal cutter 23, and has the same racks cooperating with the gears on the shaft carried by this head and operated by the ratchet 37 by means of 10 the handle 40 as previously described. It has the same clamping means for clamping the device on the edge of a door 4 or jamb 50, as in the first form. In this form, however, there is a second frame 76 for carrying the vertical blades 2 and 3 for making the vertical or outline cut for the mortise. This frame has spaced side bars 77 connected at their rear ends by a transverse angle bar 78 from which depends a pair of lugs 79 at the inner sides of the lugs 75, and to which they are pivoted by the transverse hinge pin or rod 80.

15 At their opposite or forward ends the side bars 77 are connected by the transverse bar 81 carrying a head 82 corresponding to the head 1 of the first form. At the rear and under side of this head is a recess 83 in which is mounted the upright cutter blade 3 by the screws 84 the same as in the form of Fig. 1. In this form, however, the end blades are numbered 2a, because they are in the same location and perform the same operation as the blades 2 of the first form, but are mounted somewhat differently than the blades 2 in the first form. In this 20 form the opposite ends of the head 82 are provided with upright channels 85 and the blade 2a has a reduced intermediate portion 86 which is seated in and slides in this channel, the open side of the channel being covered by spring plates 87 secured by the screws 88, these spring 25 plates being laterally curved as described in connection with the blade holders 8 of the first form, so that they are stressed to engage the blades when they are clamped in position. In this form the upper end of the blade itself is provided with a hammering head 89, instead of 30 this head being on a holder for the blade as in the first form, and the under wall 90 of this head by engaging the top wall of the head 82 forms a limit stop for limiting and determining the downward movement of the blade under the hammering operation and thus determining the depth 35 of the cut made to correspond with the thickness of the hinge butt. The head 82 is also provided with a hammering lug or surface 91 for use in driving the connecting blade 3.

In this form there are also provided on each of the 40 side bars 77 of the frame 76 a flat spring 92 secured at the under side of the bar by any suitable means, such, for example, as the rivets 93. These springs resting on top of side bars 25 of the lower frame normally hold the upper frame 76 somewhat elevated with the blades 2a and 3 spaced above the surface of the door or jamb until the device is properly located and clamped in position by the locating surface 48 and the clamp 57, as described in connection with the first form. Then after depressing the upper frame to bring the edges of the blades 45 in engagement with the edge of the door or jamb they may be driven to cut the outline cuts 55, 55a to the proper depth by hammering on the heads 91 and 89. At this time the lower surface of head 82, corresponding to surfaces 16 of the first form, rests on the surface of the door or jamb while making the outline cuts the same as in the first form.

It will be seen from the above that in each form the device may be readily and quickly applied to the edge of a door or door jamb in which the mortise is to be cut for the butt of a hinge, and then the outline cuts made first by forcing the upright blades through the material by a hammering operation, which may be easily and quickly performed, and as the blades are accurately located the mortise outline may be accurately cut to the exact size of the hinge butt and accurately to the proper

depth to correspond with the thickness of the hinge butt. Then by operating the swinging ratchet handle and shifting the horizontal blade, which is also easily and accurately located with respect to the outline cut already made, the bottom cut is easily and quickly made to remove the material between the outline cuts, and this bottom cut is accurately and uniformly made at the proper depth below the face of the door or jamb to correspond with the thickness of the hinge butt, and this bottom surface is perfectly flat and uniformly parallel with the outer surface of the door or jamb so that when the butt is seated within the recess it is located accurately parallel with this surface and not in any way tipped out of this parallel position.

It will be seen that the devices for both operations for making the outline cuts and the bottom cut are located from the outer surface in which the mortise is cut and the hinge mounted so that the outline and the bottom cuts are each properly located and cut with respect to this surface, the bottom surface being parallel thereto, for properly locating the hinge butt parallel to this surface.

Having thus set forth the nature of my invention, I claim:

1. A device for cutting a hinge butt mortise in a door or jamb comprising a head member, three upright knife blades carried by said head member, two being arranged in spaced parallel relation and the third extending between the two at one end to outline the mortise, means mounting the first two blades for vertical movement comprising upright channels in the head member open at their outer sides and spring plates extending across the open sides of the channels and stressed to maintain a frictional spring pressure against the blades in the channels locating means to engage a side face of the door or jamb to locate the blades over the surface in which the mortise is to be cut, means by which the blades may be driven into said surface to the proper depth to cut the outline of the mortise, a frame including means carrying a horizontal knife blade, said horizontal blade having a cutting edge inclined backwardly from its opposite ends to substantially the center thereof, means for clamping said frame on the door or jamb and locate the latter blade at one side of the door or jamb in alignment with said cut outline and spaced below the surface in which the mortise is to be cut a distance equal to the depth of the mortise, and means for forcing the cutting edge of the latter blade into the material of the door or jamb to make the bottom cut of the mortise and remove the material within the cut outline.

2. A device for cutting a hinge mortise in a door or jamb comprising a head member, upright knife blades carried by said member comprising an intermediate and end blades arranged with their cutting edges forming three sides of a rectangle of the size of the mortise to be cut, locating means to engage surfaces of the door or jamb to locate the blades over the surface in which the mortise is to be cut, upright guides at the opposite ends of the member in which the end blades are mounted for vertical sliding movement, said guides comprising channels open at their outer sides, spring plates extending across the open sides of the channels and stressed to maintain a frictional spring pressure against the end blades in the guides, and means whereby the blades may be driven into the door or jamb to cut the outline of the mortise.

3. A device for cutting a hinge butt mortise in a door or jamb comprising a frame including laterally spaced side bars, a transverse carrier extending between and mounted for sliding movement on said bars, a horizontal knife blade carried by said carrier, means for positioning the frame on and clamping it to a door or jamb with said blade positioned below the edge surface of the door or jamb a distance equal to the depth of the mortise to be cut, and means on the frame for shifting said carrier to force said blade into the material of the door or jamb

parallel to said surface to cut the bottom of a mortise within a previously cut outline in said surface, comprising a toothed rack on each of said side bars, a shaft mounted in the carrier, a gear pinion adjacent each end of the carrier meshing with each rack and secured to the shaft, and means to rotate the shaft to simultaneously operate the pinions to shift the carrier.

4. A device for cutting a hinge butt mortise in a door or jamb comprising a frame including laterally spaced side bars, a transverse carrier extending between and mounted for sliding movement on said bars, a horizontal knife blade mounted on said carrier, locating surfaces on the frame to cooperate with the surface of the door or jamb in which the mortise is to be cut to locate said blade below said surface a distance equal to the depth of the mortise, a transverse bar carried by said side bars provided with a transversely convex positioning surface to engage one side of the door or jamb, a clamping bar carried by the frame to engage the opposite side of the door or jamb, means for clamping said latter bar against the door or jamb to clamp the frame thereto comprising a screw having a swivel connection to the clamping bar permitting lateral rocking movement thereof, and means whereby the carrier may be shifted to force the blade into said material parallel to said surface of the door or jamb in which the mortise is to be cut to cut the bottom of the mortise.

5. A device for cutting a hinge butt mortise in a door or jamb comprising a frame including laterally spaced side bars, a transverse carrier extending between and mounted for sliding movement on said bars, a horizontal knife blade mounted on said carrier, locating surfaces on the frame to cooperate with the surface of the door or jamb in which the mortise is to be cut to locate said blade below said surface a distance equal to the depth of the mortise, a transverse bar carried by said side bars provided with a transversely and convexly curved positioning surface to engage one side of the door or jamb, a clamping means to cooperate with said transverse bar to clamp the frame to the door or jamb comprising a transverse head between and slidably mounted on the side bars, securing means for holding said head in different adjusted positions on the side bars, a clamping member carried by said head, means for clamping said clamping member against the opposite side of the door or jamb from the transverse bar to clamp the frame to the door or jamb comprising a screw having a swivel ball joint connection to the clamping member to permit lateral rocking movement of said member, and means whereby the carrier may be shifted to force the blade into the material of the door or jamb parallel to the surface in which the mortise is to be cut to cut the bottom of the mortise.

6. A device for cutting a hinge butt mortise in a door or jamb comprising a frame including laterally spaced side bars, a transverse carrier extending between and mounted for sliding movement on said bars adjacent one end thereof, a horizontal knife blade mounted on said carrier, a head member, pivot means connecting the head member to the frame adjacent the opposite end thereof for movement of the head member to and from a position over the frame, upright knife blades carried by said head member arranged with their cutting edges forming three sides of a rectangle of the size of the mortise to be cut, said pivot means forming positioning means for the head member and the upright blades carried thereby with respect to the frame and horizontal blade and also forming means whereby the head and its blades may be shifted to and from their operative positions, means for clamping the frame to the door or jamb to position the blades relative to the surface in which the mortise is to be cut, means by which the upright blades may be forced into the material of this surface to the proper depth to cut the outline of the mortise, and means whereby the horizontal blade may be then forced into the material of the

door or jamb to cut the bottom of the mortise and remove the material between the outline cuts.
